F. W. HEINS, OF NEW YORK, N. Y.

Letters Patent No. 75,680, dated March 17, 1868.

IMPROVED WASHING-MACHINE.

The Schedule referred to in these Letters Patent and making part of the same.

TO ALL WHOM IT MAY CONCERN:

Be it known that I, F. W. HEINS, of New York, 363 Third avenue, in the county and State of New York, have invented a new and improved Washing-Machine; and I do hereby declare that the following is a full, clear, and exact description thereof, which will enable those skilled in the art to make and use the same, reference being had to the accompanying drawing forming part of this specification, in which drawing—

Figure 1 represents a longitudinal vertical section of this invention.

Figure 2 is a transverse section thereof.

Similar letters indicate corresponding parts.

This invention relates to a washing-machine, the tub of which is provided with gudgeons, which have their bearings in suitable standards so that an oscillating motion can be imparted to said tub. The bottom of said oscillating tub is corrugated, so that it acts as a rubber on the clothes sliding thereon, first in one and then in the opposite direction. The top edge of the tub is strengthened by metal bars, from which project the gudgeons, and under the cover of said tub is placed a piece of wood, which stiffens the tub, and allows of securing the metal bars thereto, by means of screws, in such a manner that the gudgeons and the tub itself are enabled to sustain without injury the weight of the water and of the clothes, and also the shocks caused by the moving mass in the tub.

A represents the tub of my washing-machine, which is made of sheet zinc, or any other suitable material, in the form of the segment of an elliptic cylinder, as clearly shown in fig. 1 of the drawing. From the sides of this tub project gudgeons *a*, which have their bearings in standards *b*, rising from a suitable bed or frame, *B*, and to the ends of said tub are secured suitable hand-rails *c*, so that the operator is enabled to impart to the tub an oscillating motion. The bottom of the tub is corrugated, so that the same produces a rubbing effect on the clothes, which slide thereon back and forth as the tub receives an oscillating motion, and at the same time the water or soap-suds in the tub is brought in a violent agitation, and its effect on the clothes to be washed is materially increased. The top edge of the tub is strengthened by metal bars *d*, which also serve to give the requisite hold to the gudgeons *a*, and top part of the tub is further stiffened by a piece of board, *e*, which is secured under the metal top *f*, and which forms an additional support for the gudgeons *a*.

In practice, the metal bars *d* are secured to the tub by screws, which screw into the edges of the board *e*, and by these means the gudgeons and also the sides and ends of the tub are enabled to withstand the shocks produced by the water and the clothes moving back and forth in the tub, and also to sustain the weight of the tub and its contents without injury.

It will be seen that the bottom, *A*, is formed of a single sheet of metal, which is of elliptical form, and stamped or bent into corrugations, which are continuous of each other from one end of the sheet to the other, and therefore may be said to form the bottom and ends of an elliptical body in one piece of metal, and being corrugated throughout. The water is thus agitated on the ends as well as the bottom.

I produce a cheap device which requires no additional bottom, and dispenses with screws or equivalent means for fastening separate strips to the ordinary bottom.

The top, *f*, has a large aperture, through which the water, soap-suds, and clothes to be washed, are introduced, and which is closed by a cover, *g*. This cover is held in position by bolts or any other suitable fastenings and it is fitted into its aperture so as to produce a water-tight joint.

In a machine of this kind a large quantity of clothes can be washed in a comparatively short time, the fabric sustains no injury, and the operation of the machine is very simple, and requires comparatively little power. The tub is strong and durable, and not liable to get out of repair.

What I claim as new, and desire to secure by Letters Patent, is—

As an improvement in washing-machines, the body *A*, whose bottom and ends are formed of a single sheet of metal, bent or stamped into continuous corrugations throughout its entire length, with the strengthening-board *e*, and bars *d*, which sustain the gudgeons *a*, on which the body oscillates, substantially as and for the purpose described.

F. W. HEINS.
